LINER PULLER

Norman L. Stout and Dewey E. Owens,
Hutchinson, Kans.

Application November 20, 1947, Serial No. 787,170

1 Claim. (Cl. 29—283)

1. This invention relates to new and useful improvements in liner pullers, and the primary object of the present invention is to provide a device for removing sleeves or linings from pump cylinders or the like of various diameters.

Another important object of the present invention is to provide a liner puller including novel and improved gripping jaws so designed as to frictionally grip the lining of a cylindrical pump as the puller is extended through the pump casing.

A further object of the present invention is to provide a pump lining extractor embodying novel and improved means for actuating the gripping jaws thereof to uniformly engage the inner periphery of a lining without slipping movement relative thereto.

A still further aim of the present invention is to provide a liner puller that is simple and practical in construction, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a longitudinal fragmentary vertical sectional view through a cylinder, such as a pump cylinder, and showing the present invention installed therein for pulling a lining from the pump cylinder;

Figure 2 is a transverse horizontal sectional view taken substantially on the plane of section line 2—2 of Figure 1;

Figure 3 is a plan view of one of the gripping jaws used in conjunction with the present invention, and with parts broken away and shown in section;

Figure 4 is a perspective view of the piston rod engaging member used in conjunction with the present invention; and

Figure 5 is an elevational view of the present liner puller in slightly modified form, and with parts thereof broken away and shown in section.

Referring now to the drawings in detail, wherein, for the purpose of illustration, there is disclosed the preferred embodiment of the present invention, the numeral 10 represents a substantially cylindrical body open at both ends and provided with a fixed bearing plate 12 intermediate its ends, upon one face of which there is supported the base portion 13 of a hydraulic jack 14.

5 The movable shaft or rod 16 of this jack 14 is connected to a base member 17 having a plurality of spaced ears or fulcrums 18 that pivotally engage the inner terminal 20 of a group of radial arms 22, which are circumferentially spaced relative to each other.

10 The numeral 24 represents a plurality of articulate jaws each having an outer toothed surface 26, an angular flanged portion 28, and an integral shank portion 30 fixedly carried by the flange 28 that is provided with an eye portion 32. The eye portions 32 of the shanks 30 are provided with central slots 34 that pivotally engage the free terminal 36 of arms 22.

15 Circumferentially spaced, longitudinal slots 38 are provided in one end of the body 10 and these slots oppose the openings between pairs of spaced ears or retaining plates 40 that are rigidly secured to the inner periphery of the body 10 and 20 which are provided with opposed apertures 42 that pivotally engage the inner terminals 44 of a plurality of radial links or connecting arms 46. The outer terminals 48 of these arms 46 are bifurcated to pivotally engage the eye portions 32 of 25 the jaws 24.

In practical use of the device, the lower portion or chamber 50 provided in the body 10 engages the end 52 of a piston rod 54 that is movable or workable in the lining 56 of a pump casing or cylinder 58, and the jack 14 is operatively connected by a supply hose 59 to a hydraulic jack pump 60, so that by actuating the lever 62 of the pump 60, the base member 17 will spread relative to the body 10 and the jaws 24 and arms 22 will 30 pivot downwardly to frictionally engage the inner periphery of the lining 56 to remove the lining from the casing 58 as the piston rod 54 is actuated to force the body 10 through the pump casing 35 ing.

40 Reference is now directed to Figure 5, wherein there is disclosed the present liner puller in slightly modified form. In this embodiment, the hydraulic jack 14 is removed from its position between the base member 17 and the body 10 and 45 is replaced by a coil spring 60 that is fixedly secured at its opposite terminals 62 and 64 to the base and the bearing plate 12, respectively. In this instance, as the body 10 is forced through the pump lining by the piston rod 54, the spring 50 60 will urge the base outwardly from the body 10 to pivot arms 22 and jaws 24 downwardly, thus causing the jaws 24 to frictionally grip the inner periphery of the pump lining to remove the same from the pump casing, as the piston rod forces 55 the body 10 through the pump lining.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claim.

Having described the invention, what is claimed as new is:

A lining extracting device comprising an open ended tubular support provided with a fixed transverse bearing plate intermediate its ends, said support also having a plurality of circumferentially spaced slots at one end, arms having upper and lower end portions, the lower end portions of said arms being received in said slots for swinging movement and pivoted to said support, a group of circumferentially spaced gripping jaws having shank portions, the upper end por-

tions of said arms being pivoted to the shank portions of said jaws, a base member spaced above said support, links terminally pivoted to said base member and the shank portions of said jaws, and a jack disposed on said transverse bearing plate between said support and said base, said jack having a movable shaft abutting said base member.
